(57) **CLAIM**

The ornamental design for a shopping cart cover, as shown and described.

DESCRIPTION

FIG. 1 is a front perspective view for a shopping cart cover showing our new design in condition of use;

FIG. 2 is a rear perspective view thereof;

FIG. 3 is a rear view thereof;

FIG. 4 is a front view thereof;

FIG. 5 is a top view thereof;

FIG. 6 is a bottom view thereof;

FIG. 7 is a right side view thereof;

FIG. 8 is a left side view thereof; and,

FIG. 9 is a top unassembled view thereof, the opposite bottom view being identical.

The broken lines in FIG. 1 show environment and form no part of the claimed design.

The dashed lines in FIG. 9 of the drawings depict perforation of the shopping cart cover that form part of the claimed design.
